METHOD OF CONSTRUCTING ORNAMENTAL FIGURES

Daniel H. Greer, Pueblo, Colo.

Application June 15, 1945, Serial No. 599,609

1 Claim. (Cl. 144—309)

1
This invention relates to ornamental devices such as figures simulating birds and other creatures of substantially grotesque appearance. The present invention contemplates the manufacture of these figures from natural products such as desert pods, several of which can be cut apart and joined together to form a figure grotesquely simulating some well known bird or animal.

An important object of the invention is to offer a method whereby desert found pods and otherwise grown pods may be cut and reassembled in an orderly manner to arrive at a figure structure comically amusing in appearance.

Another object of the invention is to provide a figure reconstructed from pods or other natural objects wherein only parts of these natural objects are used in the complete construction of the figure.

A further object of the invention is to provide a figure simulating a bird constructed from parts of such pods which are naturally provided with a body portion, a stem and claws.

Various other important objects and advantages of the invention shall become apparent to the reader of the following description.

In the drawings—

Figure 1 is a side elevational view of the constructed figure.

Figure 2 is a top plan view of the constructed figure.

Figure 3 is a rear elevational view of the constructed figure.

Figure 4 is a fragmentary perspective view showing a pod after it has been cut from the vine and showing the claws fragmentary at one end and a length of the stem projecting at its opposite end.

Figure 5 is a perspective view of the natural pod after it has been preliminarily trimmed.

Figure 6 is a diagrammatic view showing fragmentarily the pod and the lines on which the pod is cut to form two legs and feet and one head section.

Figure 7 is a side elevational view of the structure represented by the diagrammatic view after it has been cut as directed by the showing in Figure 6.

Figure 8 is a side elevational view of the head section after it has been removed from the cut assembly shown in Figure 7.

Figure 9 is a perspective view of the leg and foot elements resulting from the cuts made in Figure 6.

2
Referring to the drawings wherein like numerals designate like parts, it can be seen in Figure 1 that numeral 5 denotes a natural pod such as is found in arid regions. This form of a pod is normally open longitudinally at the portion 6 and it is desirable that the pod be closed at this point in constructing the figure under the method proposed and this may be considered the first step after cutting the pod from its vine. In cutting the pod from the vine it is preferable that a length 7 of stem be left, this serves to form the neck of the resulting figure. The other end of the natural pod has a pair of slightly curved and backwardly disposed claws 8, 8, each of which has a natural hook 9 at its free end.

It will also be observed that along the open portion of the pod a form of fringe 10 normally grows and this plays a part in the resulting of a grotesque appearance of the completed figure.

After the pod has been prepared to the extent shown in Figure 5 and the open portion closed by cement or some other material or means, a second pod is prepared by cutting vertically therethrough on crossed lines a—a and b—b. The claw end portion of the body of the second pod is thus divided to form feet 11, 11 and leg members 12, 12 of the natural claws 8. This leaves a tapered portion 13 which becomes the head of the resulting figure. Considering Figure 6 the claws 12, 12 may be steamed or otherwise treated and bent laterally to the position shown in Figure 6 so that they will form upright legs when the foot portions are resting on a surface.

The method further consists in severing the hooks 9 from the resulting legs 12 on a cut c, and each side of the first pod may now be drilled or punched with an opening 14 into which is inserted and suitably secured the upper end of the corresponding leg 12. Some of the fringe or tufts 10 remain on the feet 12 by predetermination and these are denoted by reference character d and offer a definite illusionary effect in the final appearance of the figure.

Regardless of the natural disposition of the claws 8, 8 on the first prepared pod, it is preferable that they be made to overlie the body of the pod in the manner substantially shown in Figure 1.

The second pod, as illustrated in Figure 6 and more definitely shown in Figures 7 and 8 also has a length of its stem left and this is preferably ground or otherwise tapered to form 55 a bird beak 15. The beak may be steamed or

otherwise softened and bent to the desired curvature.

Seeds from the pod are split and glued or otherwise secured to the head 13 to form eye simulations 16.

The back of the head 13 is now bored or otherwise formed with an opening for receiving the preferably tapered stem and glue or other adhesive material may be placed on the stem 7 before application of the head 13, the exposed portion of the stem 7 forming a neck 7a as shown in the completed figure. (See Figure 1.)

Inasmuch as the head 13 will be inverted from the position shown in Figure 6 in the actual employment of the same in conjunction of the first pod, the fringe or tufts 10 will be underlying the head 13 as denoted by reference character 10a. This disposition of the tufts 10 along the back of the figure and depending from the head section 13 depicts a rather strange and grotesque appearance. This is amplified by the rearwardly projecting tufts 11 on the feet 11.

To effect different forms and stances, the legs 12 may be bowed or one disposed in front of the other and the head may be cocked on the neck 7a or the neck bent laterally, downwardly or upwardly to give the desired animated effect to the bird or other species.

Such a figure will be highly ornamental and while comical and grotesque in appearance will be extremely amusing and pleasing.

Inasmuch as the hooks 9 on the first pod will be substantially over the center of gravity of the figure, the figure may be supported by these hooks, one or the other. The figure will substantially balance when supported by one of these hooks resting on a person's finger.

While the foregoing description sets forth the invention in specific terms, it is to be understood

that numerous changes in shape, size and materials may be resorted to without departing from the spirit and scope of the invention as claimed hereinafter.

Having described the invention what is claimed as new is:

A method of constructing figures from pods of the species having a body, claws and a stem and a longitudinal opening in said body; cutting a pod from a vine leaving a portion of stem projecting from its body to define its neck, cementing the edges of the longitudinal opening, forming holes in the sides of the pod's body, cutting a second pod on crossed lines crossing at the claw end of the pod body to define a pair of feet and two legs of said claws and a head section, cutting said claws of the second pod and inserting the cut ends into the openings of the body of the first pod and applying the head section to the neck forming the stem of the first pod, the body portion of said pods having fringe-like formations on the top side thereof, said head section being inverted when applied on the stem of the first pod so that its fringe will be depending.
